(57) **CLAIM**

The ornamental design for a terminal of card socket, as shown and described.

DESCRIPTION

FIG. 1 is a top, front, and left side perspective view of a terminal of a card socket, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a top, front, and left side perspective view thereof, in use condition;

FIG. 9 is an exploded top, front, and left side perspective view thereof shown with another electrical contact; and,

FIG. 10 is a top, front, and left side perspective view thereof shown with another electrical contact.

The broken lines are included for the purpose of illustrating environment and forms no part of the claimed design.
